UNITED STATES PATENT OFFICE.

GEORGE H. TAYLOR, OF NEW YORK, N. Y.

DESIGN FOR TRIMMING.

SPECIFICATION forming part of Design No. 23,073, dated February 20, 1894.

Application filed December 15, 1893. Serial No. 493,775. Term of patent 14 years.

To all whom it may concern:

Be it known that I, GEORGE H. TAYLOR, a citizen of the United States, residing in the city, county and State of New York, have invented and produced a new and original Design for Trimmings, of which the following is a description, reference being had to the accompanying drawings, wherein—

Figure 1 is a face view of a piece of fabric embodying my design. Fig. 2 is a transverse section through the same. Fig. 3 is an edge view of the same, looking from one side.

The essential feature of my design consists in the corrugated or scalloped surface of a trimming wherein one series of corrugations or scallops run at an angle to another series of corrugations, as illustrated in Fig. 1.

In the drawings A designates one series of corrugations, and B another series of corrugations, which are shown extending at right angles to said series of corrugations A; while C indicates a third series of corrugations extending at an angle to the next adjacent series of corrugations B.

Having described my invention, what I claim is—

The design for trimmings, substantially as shown and described.

GEORGE H. TAYLOR.
